UNITED STATES PATENT OFFICE.

HOWARD M. DUDLEY, OF PHILADELPHIA, PENNSYLVANIA.

DYEING-MACHINE.

1,259,839.

Specification of Letters Patent. Patented Mar. 19, 1918.

Application filed March 29, 1917. Serial No. 158,201.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to improvements in dyeing machines and refers particularly to dyeing machines adapted to the dyeing of piece goods.

In the dyeing of goods in the piece, the greatest care must be exercised in order to cause complete penetration of the dyestuff and produce even shades.

The dyeings of many dyestuffs require an after-treatment with such products as metallic-salts, or oxidizing agents in order to develop the best results. It is also necessary to thoroughly wash the goods at various stages of the operation and to dry them when finished.

As each one of these operations has an effect upon the results, it is essential that all of the treatments be uniform throughout the fiber and that they be readily controlled.

One object of my invention is a device in which the piece goods may be uniformly subjected to a solution of a dye.

Another object of my invention is a device in which thorough penetration of textile fabrics may be effected.

Another object of my invention is a device in which dyed fabrics may be uniformly and thoroughly after-treated with a liquid, air or other gas.

Another object of my invention is a device in which the fabrics may be thoroughly dried.

Another object of my invention is a device in which fabrics may be dyed, washed, after-treated and dried in a thorough and uniform manner without handling them.

Other objects of my invention will be evident upon a consideration of my specification and claims.

In the accompanying drawings, which illustrate one form of a device of my invention, similar parts are designated by similar numerals.

Figure 1 is a top-plan view of one form of my invention.

Fig. 2 is a section through the line 2—2 of Fig. 3.

Fig. 3 is a cross-section of the dyeing chamber through the line 3—3 of Fig. 2.

Fig. 4 is a broken enlarged cross-section showing a foraminous plate, the fabric and the surrounding belt or cover.

Fig. 5 is a cross-section through the line 5—5 of Fig. 3 with the fabric and surrounding belt or cover removed.

Fig. 6 is a broken top plan view of a foraminous plate.

The particular form of my device, as illustrated, comprises a dyeing chamber formed by the bottom member 7 and the top member 8, hingedly attached thereto and capable of being held in intimate contact by means of the bolts 9, 9. A pipe 10, opening into the top of the dyeing chamber is connected to the valve 11, which in turn is connected to the pipes 12, 13, having the flange joint 14. The pipe 13 opens into the top of a liquid reserve tank 15. The pipe 13 has the valve 60 and is connected with the pipe 61 carrying the valve 62.

Within the dyeing chamber is a reel, around which the cloth to be dyed or treated is wound, comprising the two end flanges 16, 16^A, to which are fixedly attached the two foraminous plates 17, 18. The two flanges 16, 16^A extend into the shells 19, 19^A of the hollow core of the reel extending outwardly from opposite ends of the dyeing chamber. Fixedly attached to the shell 19 is a cogged wheel 20, meshing with the worm gear 21 which is fixedly attached to the shaft 22, which in turn is fixedly attached to the two gear wheels 23, 24. The gear wheel 25 is attached to the shaft 26 from which revolution is given the gear wheel 25. By means of the lever-arm 27, the wheel 25 may be retained in a neutral position or may be meshed with either the wheels 23 or 24, thus imparting a revoluble movement to the shells 19, 19^A and the reel in either direction as desired. Extending into the shells 19, 19^A are the pipes 28, 28^A around which the shells 19, 19^A are revoluble. The pipes 28, 28^A are connected to the pipes 29, 29^A by means of the flange joints 30, 30^A.

A series of tubes 31, 31^A, 32, 32^A connect the entire inner face of the foraminous plate 17 with the exterior portion of the chamber formed by the shells 19, 19^A, the tubes from the chamber of the shell 19 alternating upon the foraminous plate 17 with the tubes from the chamber of the shell 19^A, i. e. adjacent

tube openings upon the plate 17 extend oppositely to each other and outwardly through the shells 19, 19^A. Within each tube 31, 31^A, 32, 32^A is a series of saw-toothed baffle-
5 plates 33, 33, 33, of varying lengths.

A perforated steam pipe 61 is within the dyeing chamber in order to maintain the proper temperature of the liquid.

The foraminous plate 18 has a series of up-
10 wardly and downwardly extended pyramids 34, 34 between which is a series of openings 35, 35.

A drain cock 36 is situated at the bottom of the dyeing chamber.

15 The pipes 29, 29^A are connected to the pumps 37, 37^A. The pumps 37, 37^A are connected to the two-way pipes 39, 39^A having the valves 40, 40^A, 41, 41^A, and also to the four-way pipes 42, 42^A having the valves 20 43, 43^A, 44, 44^A, 45, 45^A. The valves 43, 43^A are connected with the pipes 46, 46^A which in turn are connected with a tank (not shown) containing dyeing liquor. The valves 44, 44^A are connected with a source 25 of water supply. The valves 45, 45^A are connected with the pipes 47, 47^A which enter the bottom of the liquid supply tank 15 by means of the pipe 48.

The cloth 49 wrapped or rolled around 30 the foraminous plate 18, is surrounded or covered by a foraminous covering or link belt 54 comprising a series of links pivotally connected by the pivots 53, 53 and capable of permanent adjustment and engagement 35 by means of the threaded bolt 50 and the two end members 51, 52. This belt or covering 54 has pyramidal members 55, 55, and openings 56, 56, similar to those in the foraminous plate 18, and the links are removable in order to shorten or lengthen the belt 54.

40 The operation of the device is as follows, it being assumed that the device is in proper condition for dyeing:—All of the valves 45 with the exception of 43, 43^A, 11 and 60 are closed, and the pumps 37 and 37^A started. This draws the liquid from the dissolving tank (not shown) through the pipes 46, 46^A, 42, 42^A and forces it through the pipes 50 29, 29^A, 28, 28^A into the chambers of the outwardly extended shells 19, 19^A. From here the liquid is forced through the tubes 31, 31^A, 32, 32^A, the baffle plates 33, 33 serving to equalize the distribution of the flow and 55 force of the liquid, through the foraminous plate 17, into the chamber 57, through the foraminous plate 18, outwardly through the piece goods 49, through the foraminous belt 54 and through the pipes 10, 12, 13 into the 60 liquid reserve tank 15. The object of this tank 15 is to retain a large quantity of liquor, the use of which will produce much more satisfactory results than will a smaller quantity. When enough liquor has been drawn 65 through the pipes 46, 46^A, the valves 43, 43^A

are closed and the valves 45, 45^A opened, and thus a complete circulation of the liquor in the tank 15 is obtained. During the dyeing process the reel and the goods thereon and the two shells 19, 19^A are continuously re- 70 volved within the dyeing chamber which is full of the dyeing liquor.

When the dyeing operation is finished, the valves 45, 45^A and 60 are closed, and the valve 36 opened, thus drawing all of the 75 dye liquor from the dyeing chamber. Valves 44, 44^A and 62 are then opened, and the goods are washed by water introduced through the valves 44, 44^A to the pumps 37, 37^A, which forces it through the device in 80 exactly the same manner as employed with the dye liquor but the wash water escapes through the pipe 61 to a drain, if desired. The oxidizing or drying of the goods may be accomplished in several ways in order to 85 meet the particular demands. Valves 44, 44^A are closed, valves 40, 40^A opened, the pumps 37, 37^A stopped and pipe 61 connected with a vacuum pump. This will draw air through the valves 40, 40^A and through the 90 entire device, if desired. Valves 40, 40^A may be closed, and air of the required temperature forced through the valves 41, 41^A by means of a force pump. The goods having been thus dyed, washed, oxidized and dried, 95 the flanges 30, 30^A and 14 are disconnected, the bolts 9, 9, removed and the top member 8 of the dyeing chamber opened upon its hinge. The reel with the goods contained thereon, the shells 19, 19^A and the pipes 28, 28^A can then be hoisted from within the dyeing chamber by any suitable means. The belt or covering 54 is removed and the goods 100 unwound from the reel. A quantity of undyed goods are wound upon the reel, the belt or covering 54 placed around the goods 105 and held in tight engagement therewith by means of the screw bolt 50 and the end pieces 51, 52. The reel with its attachments placed within the dyeing chamber, the top 8 closed and fixed to the bottom member 7 by means of the bolts 9, 9, forming a water and air tight joint between the two, the flanges 30, 30^A and 14 are tightly joined and the apparatus is in position for the dyeing operation. 110

It is evident that, if desired, the reel need not be withdrawn from the dyeing chamber in order to remove the fabric or roll a new lot of fabric thereon. In this event, the top 115 member 8 of the dyeing chamber may be opened upon its hinge, and the reel revolved in order to allow the fabric to be withdrawn therefrom and the empty reel thereupon being revolved in the opposite direction to cause the fabric to be wound upon it.

It is thus seen that a very considerable amount of time, space and labor are saved by the use of my device, over those generally employed, in which the goods are continu- 120 125 130

ally rolled up and un-rolled during the operations.

By the uss of a device of my invention, the fabric is wound upon a reel and all of 5 the operations are conducted under exactly the same conditions, without rewinding the fabric, thus insuring uniform results at greatly decreased costs.

I do not limit myself to the particular 10 size, number, form or arrangement of parts as described and illustrated, all of which may be varied without going beyond the scope of my invention as described and claimed.

15 What is claimed, is:

1. In a dyeing machine, in combination, a hollow reel comprising imperforate flanges and a perforate body, a foraminous member surrounding the body and spaced therefrom, 20 a foraminous member capable of adjustment under pressure upon fabric wrapped around the first mentioned foraminous member, a chamber in which said reel is revolvably carried, a series of tubes connecting the 25 inner face of the perforate body with a source of liquid supply and means for revolving the reel and the tubes.

2. In a dyeing machine, in combination, a hollow reel comprising imperforate flanges 30 and a perforate body, a foraminous member surrounding the body and spaced therefrom, a foraminous member capable of adjustment under pressure upon fabric wrapped around the first mentioned foraminous member, a 35 chamber in which said reel is revolvably carried, a series of tubes connecting the entire inner face of the perforate body with sources of liquid supply, adjacent tubes upon the face of the perforate body extending in 40 opposite directions through the reel to such sources of liquid supply, said tubes being integral to the reel and revoluble therewith and means for revolving the reel.

3. In a dyeing machine, in combination, 45 a dyeing receptacle, a hollow reel revoluble within the receptacle, the reel comprising outwardly extended imperforate flanges connected by means of a perforate body, a foraminous member parallel to the body and 50 spaced therefrom, a jointed foraminous belt capable of tight adjustment around fabric carried by the body, means for conveying liquid to the inner face of the perforate body from opposite ends of the reel, said 55 means being revoluble with the reel, means

for breaking the flow of liquid through said liquid conveying means, means for revolving the reel within the dyeing chamber, means for forcing liquid through the reel, the perforate body, the foraminous plate, 60 the fabric and the foraminous belt while the reel is in revoluble motion and means for withdrawing the liquid from the dyeing chamber.

4. In a dyeing machine, in combination, 65 a dyeing receptacle, a hollow reel revoluble within the receptacle, the reel comprising outwardly extended imperforate flanges connected by means of a perforate body, a foraminous member parallel to the body and 70 spaced therefrom, a jointed foraminous belt capable of tight adjustment around fabric carried by the body, means for conveying liquid to the inner face of the perforate body from opposite ends of the reel, said 75 means being revoluble with the reel, means for breaking the flow of liquid through said liquid conveying means, means for revolving the reel within the dyeing chamber, means for forcing liquid or air through the 80 reel, the perforate body, the foraminous plate, the fabric and the foraminous belt while the reel is in revoluble motion, means for returning it to the liquid forcing means and means for withdrawing the liquid from 85 the dyeing chamber.

5. In a dyeing machine, in combination, a hollow reel, comprising imperforate flanges and a perforate body, a foraminous member comprising a series of upwardly and downwardly extended pyramids with liquid passages therethrough, said foraminous member surrounding the body and spaced therefrom, a foraminous cover similar in form to the foraminous member capable of tight adjustment around fabric carried by the foraminous member, a series of tubes connecting the inner face of the perforate body with a source of liquid supply, means within the tubes for distributing a liquid equally over 100 the inner face of the perforate body, said tubes being integral with the reel and revoluble therewith, a receptacle in which the reel is revoluble, means for revolving the reel and means for withdrawing a liquid from 105 the receptacle.

Signed at New York city, in the county of New York and State of New York, this 26 day of March, 1917.

HOWARD M. DUDLEY.
